CLAIM

The ornamental design for a monitor arm, as shown and described.

DESCRIPTION

FIG. 1 is a first perspective view of a monitor arm showing our new design;

FIG. 2 is an enlarged view of portion 2 of FIG. 1;

FIG. 3 is a second perspective view thereof;

FIG. 4 is a third perspective view thereof;

FIG. 5 is a left side elevation view thereof;

FIG. 6 is a right side elevation view thereof;

FIG. 7 is a rear elevation view thereof;

FIG. 8 is a front elevation view thereof;

FIG. 9 is a top plan view thereof;

FIG. 10 is a bottom plan view thereof; and,

FIG. 11 is a perspective view of the thereof, shown in an environment.
The broken lines depict environment and the bounds of the enlargement. The broken lines form no part of the claimed design.

1 Claim, 11 Drawing Sheets
